PETER CAMPBELL, OF ST. JOHN, NEW BRUNSWICK, CANADA.

ACETYLENE-GAS GENERATOR.

1,188,039.

Specification of Letters Patent. Patented June 20, 1916.

Application filed May 27, 1913. Serial No. 770,145.

To all whom it may concern:

Be it known that I, PETER CAMPBELL, a subject of the King of Great Britain, residing at St. John, in the Province of New 5 Brunswick, Dominion of Canada, have invented certain new and useful Improvements in Acetylene-Gas Generators, of which the following is a specification.

My invention relates to improvements in 10 acetylene gas generators and the object of the invention is to devise a generator in which the mechanism or leverage operating valves is partly submerged and water sealed thus doing away with the necessity of using 15 stuffing boxes or other similar means which interfere with the working of the valves clogging same with waste or residue.

The invention consists of the parts constructed and arranged all as hereinafter 20 more particularly described and illustrated in the accompanying drawing in which:

Figure 1 represents a vertical section through a generator constructed according to my invention. Fig. 2 is a fragmentary 25 perspective of the upper chamber and bell member of the generator showing the location of the mechanism whereby the feed valve is rendered inoperative.

1 is the base portion of the generator forming 30 a lower water chamber and having a sloping bottom 2.

3 is the upper water chamber having a semi-circular and vertically disposed projection 4 in its periphery.

35 5 is a central tube open at the bottom to the lower water chamber, and extending up above the water chamber 3.

6 is a vertically disposed projecting member secured to the periphery of the lower 40 chamber and communicating therewith.

7 is a chamber located below the upper water chamber 3.

8 is a suitable pipe extending up into the water chamber 3 for a certain distance, and 45 9 is a cap extending down over the top of the pipe 8 for considerable distance, and 10 is a rod secured to the cap 9 and extending down through the pipe 8 and then up outside the generator as will be more fully described later on.

11 is a suitable surface blow-off pipe leading from the chamber 7 up outside the generator and designed to connect with the main blow off pipe 12, which is formed with two 55 branches, one of the said branches projecting

up through the bottom of the chamber 3 for a certain distance. 13 is the gas supply pipe which also extends up through the chamber 3 for a certain height, the lower portion of the gas supply pipe being turned at right 60 angles and extending out the side of the lower water chamber 1.

14 is a carbide container of cylindrical form within the central tube, said container having a bottom formed like an inverted frustum of a hollow cone, such bottom being provided with a valve seat mounted around the lower edge thereof.

17 represents a perforated diaphragm extending transversely across the carbide container 14, such diaphragm carrying an inverted cylinder 18 designed to be located above the valve seat 16.

19 is a double ball valve having a spindle 33 connected thereto extending up through 75 the top of the generator, the inner ball 19^a being on the upper side of the valve seat 16 and the outer ball 19^b being on the lower side of the same.

20 is an annular bell shaped member surrounding the central tube 5.

21 is a cylindrical cover extending down over the carbide container.

22 is a suitable pipe secured to the under side of the bell member 20, and designed 85 to extend down over the blow off pipe 12, said pipe having a suitable aperture 22^a.

23 are brackets on the top of the bell member 20 designed to have the wheels 24 journaled thereto.

25 are guide rods extending upward from the upper water chamber upon which the wheels 24 are designed to rotate when the bell member 20 rises or falls in the upper water chamber 3.

26 is a rod designed to extend up through the projection 4 and having a pin 26^a thereon designed to engage a suitable projection 27 on the upper rim of the upper water chamber. The lower end of the rod 26 is 100 pivotally connected to a lever 28 which has its fulcrum in the standard 29 at the bottom of the upper water chamber. 30 is a lever mounted on the top of the carbide container 14 and having its fulcrum in the standard 105 31 which is mounted toward the side edge of the upper end of the said container.

32 is a link which pivotally connects the lever 30 to the lever 28.

33 is a valve spindle carrying the two balls 110

19^a and 19^b of the valve 19 and pivotally connected at its top to the lever 30. The down pressure of the projection 27 on the bell member 20 upon the pin 26^a attached to 5 the rod 26 causes the levers to lift the valve spindle and thus feed carbide, whereas if the bell member rises through the generation of the acetylene gas the valve is closed by the weight of the balls 19^a and 19^b of the valve 10 19 stopping further generation. The projection 6 of the lower water chamber 1 has an overflow trough 34 formed by the partition 36, such trough having a discharge vent 35 near the bottom thereof. The trough 34 15 is designed to take the overflow from the lower water chamber.

37 is a rod extending down through the lower water chamber 1 connected to and designed to operate an agitator 38 located 20 above the inclined bottom of the said lower water chamber.

39 is a water level indicator which floats in the water in the lower water chamber such indicator having a small rod 40 connected to 25 its upper end extending through the guide 41 the said rod being designed to indicate any fluctuation of the water level in the lower chamber.

42 is a cock at the bottom of the lower water chamber, for draining off the sludge and water. On the surface blow-off pipe 11, a cock 43 is mounted, such cock being actuated by the lever 44 which is provided with a slot 45 therein. The rod 10 is provided intermediate of its ends with a pin 47 preferably formed integral therewith which engages with the slot 45. The upper end of the rod 10 is bent in the form of an inverted U and extends above the cover of the carbide container and is connected to a lever 48 which is provided with a cam shaped end and operates the interlocking gear 49 on the top of the cylindrical cover 21. The lower end of the rod 10 is bent into a U near 45 the bottom of the lower water chamber and extends upward and is secured to the cap 9 over the gas delivery pipe 8. At a certain point of the rod 10 a pin 70 engages one end of the crank lever 71 attached to the body 50 of the generator, the other end of the said lever engaging the bifurcated end of the link 72 located at the rim of the upper chamber and provided at the other end with an orifice therethrough designed to slidably engage 55 the trip rod 26.

The interlocking gear 49 consists of a standard 52 secured to the top of the carbide container cover 21 adjacent to the winged head 54 of the feed cock 53, the lever 48 60 being pivotally mounted in the said standard and so designed that when raised at the outer end it engages the winged head 54 of the cock 53, thereby preventing the said cock being opened, and when lowered the 65 winged head 54 is capable of being rotated

into a vertical position in which it engages the lever 48. It will be understood that when the lever 48 is in this depressed condition, the cap 9 is pressed downwardly on the pipe 8, the valve 43 being simultaneously 70 opened through the medium of the lever 44 which, due to the engagement of the slot 45 with the pins 47, actuates the rod 10, which in turn transmits its motion to the lever 48 and the cap 9. Simultaneously with the operating of the lever 44 to press the rod 10 downwardly, the pin 70 actuates the crank lever 71 which in turn transmits its motion to the slotted bolt 72 and actuates the rod 26 so that the pin 26^a is disengaged from 75 the projection 27.

When it is desired to fill or empty the generator the lever 44 is fully raised up opening the cock 43 and admitting air into the generator, the cap 9 over the delivery pipe 8 80 being simultaneously pressed down tightly preventing any gas from returning to the generating chamber or the water from siphoning through from the upper water chamber into the lower and at the same time moves the rod 26 laterally, thereby disengaging the pin 26^a from beneath the projection 27 on the bell as well as operates the interlocking gear lever 48 and permits of the feed cock 53 being opened in which position 85 the winged head 54 engages and locks the lever 48 in position.

55 is a heavy grid ring designed to be inserted into the carbide container on top of the carbide and to press same down, said ring 90 surrounding the valve spindle.

56 is a chain connected to the ring 55 and passing over a pulley 57 on the top of the carbide container cover and also over a pulley 58 on the top edge of the same and down around pulleys 59 and 60 at the bottom of the upper chamber and then up and around a pulley 61 on the rim of the upper chamber, and down a certain distance on the outside of the generator terminating in 100 a suitable balance weight 62. The height of carbide in the carbide container can be determined readily by referring to the side of the generator which may have a suitable index and the weight will register on the index how much carbide is in the container. The ring can be pulled up by the chain when filling the container with carbide and held in place by having an aperture in the weight into which a pin at the lower end 105 of the index is inserted.

It will be seen that the operation of the valves by a mechanism which is partly submerged and wholly covered at all points will obviate the necessity of having stuffing 110 boxes which are liable to clog with waste or residue and thus interfere with the operation thereof. Further it will be seen that the valves having been properly adjusted the pressure on the pin 26^a by the pro- 115

jection 27 depresses the rod 26 and through the medium of the lever 28, the link 32 and the lever 30 actuates the valve spindle, raising the upper valve ball 19^a sufficiently to allow the carbide to feed through into the lower water chamber—, and as the gas is generated the bell member is raised so that the projection 27 is disengaged from the pin 26^a permitting the ball 19^b to engage with the valve seat 16.

What I claim as my invention is:

1. In an acetylene gas generator and in combination, an upper chamber, a carbide container located in the upper chamber, a feed cock mounted on the carbide container, a pivotally mounted interlocking lever provided with a cam end coöperating with the feed cock, a pipe extending into the upper chamber, a cap slidably mounted on the pipe, a rod operatively connecting the cap and the interlocking lever, and means for simultaneously operating the said cap and lever.

2. In an acetylene gas generator, an upper chamber, a carbide container located in the upper chamber, a valve operating in the container, a vertical rod operatively connected to the valve, a pin on said rod, a bell member in the upper chamber, a projection on the bell member coöperating with the pin on the vertical rod, a lower chamber, a pipe extending into the upper chamber, a cap on the pipe, a surface blow-off pipe, a cock mounted on the surface blow off pipe, and means for simultaneously operating the cap and cock and moving the vertical rod laterally.

3. In an acetylene gas generator, an upper chamber, a carbide container in the chamber, a valve operating in the carbide container, a rod operatively connected to the valve, a pin on the rod, a bell member in the upper chamber, a projection on the bell member adapted to engage the said pin, a lower chamber, a pipe extending into the upper chamber, a cap on the pipe, a surface blow off pipe in the lower chamber, a cock mounted on the said blow off pipe, a feed cock on the carbide container, a locking lever controlling the operation of the feed cock, and means for simultaneously operating the cap, cock and interlocking lever and moving the first said rod laterally.

4. In an acetylene gas generator, an upper chamber, a carbide container in the upper chamber, a valve in the carbide container, a rod operatively connected to the valve, a pin on the rod, a bell member in the upper chamber, a projection mounted on the bell member designed to engage with the said pin, a lower chamber, a pipe extending into the upper chamber, a cap on the pipe, a feed cock on the carbide container, an interlocking lever coacting with the said feed cock, a rod engaging at one end the said interlocking lever and at the other end the said cap, a pin intermediate of the ends of the said rod, a surface blow-off pipe on the lower chamber, a cock mounted on the said pipe, a lever on the said cock adapted to engage the pin on the last said rod, and means operated by the said lever designed to engage and disengage the first said rod with the projection on the bell member, as and for the purpose specified.

5. In an acetylene gas generator, an upper chamber, a carbide container suitably retained therein, a valve in the container, a rod operatively connected to the valve, a pin on said rod, a bell member in the upper chamber, a projection mounted on the bell adapted to engage with the said pin, a lower chamber, a pipe extending into the upper chamber, a cap thereon, a feed cock, a pivotally mounted interlocking lever coacting with the said feed cock, a rod engaging at one end the interlocking lever and at the other end the said cap, a pin intermediate of the ends of the said rod, a blow-off pipe on the lower chamber, a cock mounted on the said pipe, a lever on the said cock adapted to engage the pin on the last said rod, a crank lever pivotally mounted to the generator having one end engaging the last said rod, a slotted bolt connected at one end to the crank lever and at the other end to the first said rod, as and for the purpose specified.

In witness whereof I have hereunto set my hand in the presence of two witnesses.

PETER CAMPBELL.
